UNITED STATES PATENT OFFICE

2,539,738

ENGINE GOVERNOR

George B. Grim, Washington, and Kenneth J. Fleck, Peoria, Ill., assignors to Caterpillar Tractor Co., Peoria, Ill., a corporation of California

Application October 20, 1948, Serial No. 55,506

2 Claims. (Cl. 264—3)

1

This invention relates to governors in general and more particularly to a governor of the centrifugal type for varying the quantity of fuel supplied to an engine in response to changes in engine load.

It is conventional practice, in an engine employing one or more fuel pumps for metering the quantity of fuel supplied to each of the working cylinders, to associate a flyweight governor with a fuel pump control member in such a manner that the action of the flyweights under centrifugal force urges the fuel control member in a direction to decrease the quantity of fuel metered to the engine. A main governor spring is normally associated with the fuel pump control member in such a manner that its force opposes the action of the flyweights. The governed speed of the engine is controlled manually by a lever associated with the spring in such a manner that the force of the spring opposing the flyweights is determined by the load applied to the spring by the manual control lever. A suitable stop is usually provided to limit the movement of the fuel pump control in a direction to increase the fuel supplied to the engine thus limiting its maximum output.

In this type of governor, the speed differential between "no load governed speed" and the speed of the engine at "full load" increases as the governed speed of the engine is decreased. This is caused by the force exerted by the flyweights decreasing with the square of the engine speed while the force exerted by the governor spring decreases directly with its deflection. Thus at lower governed speeds, a greater change in speed is required to allow the governor spring to move the fuel control member to its fully opened position than would be required at a higher speed. As a result, under some operating conditions, the engine will stall before the fuel metering control member reaches its fully opened position.

This characteristic is undesirable in most applications and is particularly so for vehicles such as tractors or the like. In such a vehicle which may operate over rough terrain or in narrow confines, it is often desirable to reduce the governed speed of the engine to ease into or assume a load gradually and still be able to exert maximum engine torque without further manipulation of the manual control. However, if the load applied to the governor spring to give a satisfactory "no load" speed is not sufficient to effect movement of the fuel control member to its fully opened position, the vehicle will either stall or be required to operate at reduced torque unless the operator moves the manual control lever to increase the

2

load on the governor spring. Due to the number of manually operated controls necessary to guide the tractor and control various tractor-mounted or tractor drawn implements, it is impractical under many circumstances for the operator to devote one hand to the manipulation of the governor control.

This condition is particularly aggravated when a yieldable fuel stop or the like is associated with the fuel control member to establish a so-called "rated output" of the engine below its maximum. Such devices oppose the action of the governor spring and require an additional force to achieve full travel of the fuel metering control member.

15 It is, therefore, an object of this present invention to provide an engine governor that will permit full travel of the fuel pump control member throughout the governed speed range of the engine. Another object of this invention is to provide an engine governor that will maintain a constant speed differential between no load governed speed and full load at any governor setting. It is a further object of this invention to provide a yieldable stop associated with the fuel control 20 member which permits additional movement of the fuel control member when the engine is loaded beyond its rated load, such stop being so arranged that it requires a lesser deflection to permit full travel of the fuel metering control member as the governed speed of the engine is decreased.

25 Other objects and advantages will be made apparent in the following specification wherein reference is made to the accompanying drawings.

30 In the drawings:

Fig. 1 is a schematic longitudinal sectional view through a governor incorporating the present invention;

35 Fig. 2 is an enlarged sectional view taken along the line II—II of Fig. 1;

Fig. 3 is a longitudinal sectional view similar to Fig. 1 illustrating the governor in its position at full rated load;

40 Fig. 4 is a longitudinal sectional view through a governor embodying a modified form of the invention illustrating the various parts in their position at maximum governed speed with no load on the engine;

45 Fig. 5 is a view similar to Fig. 4 illustrating the parts in their position at full rated load;

Fig. 6 is a view taken along the line VI—VI of Fig. 4; and

50 Fig. 7 illustrates typical performance curves of an engine provided with a governor of this invention in contrast to an engine provided with a conventional governor.

In Fig. 1 of the drawings, a fuel pump housing of an internal combustion engine (not shown) is illustrated at 10 as enclosing a plurality of fuel pumps 11. The number of fuel pumps conventionally corresponds to the number of engine cylinders and are of a well-known type in which rotary movement of plungers 12 operates to vary the quantity of fuel delivered to the engine cylinders upon each stroke of the plungers. Each plunger is provided with a gear 13 meshing with and rotated by movement of a rack bar 14 extending through and supported for reciprocation in the housing 10. One end of the rack bar is pivotally connected to a link 15 which in turn is pivotally connected to a lever 16, pivotally supported from a bracket 17 extending from a suitable engine housing or the like indicated at 18. A roller 19 is carried for rotation in the opposite end of the lever and is adapted to engage a flanged sleeve 20, supported for rotation as well as sliding movement on an extending end 21 of an engine camshaft 22. The camshaft 22 is provided with a collar 23 having a pair of extending ears 24 which serve as the pivotal support for a pair of flyweights 25. The flyweights are provided with inwardly extending fingers 26 adapted to engage the flanged end of the sleeve 20. During operation of the engine, the flyweights tend to swing outwardly urging the collar 20 to the right, as viewed in Fig. 1, thus moving the lever 16 and rack bar 14 in a direction to decrease the amount of fuel metered to the engine.

Movement of the rack bar 14 in a direction to decrease the fuel is opposed by a governor spring 28, enclosed within a housing 29, secured to the fuel pump housing as by cap screws, one of which is illustrated at 31. One end of the spring 28 is pivotally connected to an anchor 32 extending from the housing 29 and its opposite end is connected to a pin 33 extending through an elongated slot 34 formed in a lever 35. One end of the lever 35 is pivotally supported from the housing 29 by means of a shaft 36 and its opposite end is pivotally connected to a link 37, which in turn is pivotally connected to the rack bar 14. The force exerted by the spring on the lever 35 urges it to pivot in a counter-clockwise direction, as viewed in Figs. 1 and 3, about the shaft 36, moving the rack bar in a direction to increase the quantity of fuel metered to the engine in opposition to the action of the flyweights. Movement of the rack bar in a direction to increase the amount of fuel metered to the engine is limited by a pair of lock nuts 38 threaded on the rack bar 14 and adapted to abut the housing 29 in the maximum fuel position, thus limiting the maximum power output of the engine.

As is best illustrated in Fig. 2, the pin 33 also extends through a pair of elongated slots 39, one of which is provided in each of a pair of arms 40 forming a part of a bifurcated control lever 41. The pin is held against axial movement within the slots by an enlarged head 42 formed on one end and by a washer 43 and cotter pin 44 associated with the opposite end. The lever 41 is pivotally supported from the housing 29 by means of pins 45, one of which is received in a suitable opening provided in each of the arms 40. The lever 41 extends through a slotted opening 46 (Fig. 1) provided in the housing 29 and at its extending end is pivotally connected to a control rod, a part of which is illustrated at 47 which may extend to any suitable manual control mechanism (not shown).

Selection of the governed speed of the engine

is accomplished by rocking the control lever 41 about its pivotal support causing the pin 33 to slide within the slot 34, as well as sliding within the slots 39 within the arms 40. Movement of the pin 33 within slot 34 changes the point of application of the force exerted by the governor spring 28 on the lever 35, thus changing the lever ratio of the spring force acting on the rack bar 14 in opposition to the force exerted by the flyweights.

The governor spring is preloaded an amount determined by the maximum governed speed of the engine at the time of assembly. Its length, and as a result the force exerted by it on the lever 35, remains substantially constant throughout the no load governed speed of the engine as, during changes in the governed speed of the engine, the spring is rocked about its pivotal connection to the governor housing. As a result, the spring is always deflected sufficiently to insure full travel of the rack bar at any governor setting.

A second spring 48 is also pivotally connected at one end to the pin 33 and at its opposite end to a pin 49 disposed within an elongated slot 50 provided in a plate member 51 adjustably secured to the housing 29 as by cap screws 52. Under normal operating conditions, the spring 48 is free to follow the action of the governor spring 28 until the pin 49 reaches the end of the slot 50. At this time, further movement of the rack bar 14 in a direction to increase the amount of fuel supplied to the engine is opposed by the pin 49 engaging the end of the slot 50, thus establishing a so-called rated load for the engine. However, when an additional load is placed on the engine decreasing its speed, the spring 48 will be deflected by the governor spring permitting further movement of the slide bar 14 in a direction to increase the supply of fuel to the engine until the stop nuts 38 abut the housing 29. This increased amount of fuel results in greater engine torque and may be adjusted to give the particular torque characteristics desired. As the spring 48 is pivotally connected to the pin 33, rocking of the control lever 41 causes the spring 48 also to rock about the pin 49 in the same manner as the governor spring. Thus, at lower governed speeds, a lesser deflection of the torque spring 48 is required to achieve full travel of the rack bar due to the change in the lever ratio.

In operation, selection of the governed speed of the engine is accomplished by rocking the control lever 41 about its pivotal support causing the pin 33 to slide within the slot 34 of lever 35. In Fig. 1, the various elements of the governor are illustrated in the positions they will assume at maximum governed speed with no load on the engine. At this time, the pin 33 is at the lower end of the slot 34 in lever 35, thus the force of the spring 28 is acting with the greatest lever ratio against the force of the flyweights. When a load is applied to the engine, decreasing its speed, the force exerted by the flyweights will become less permitting the governor spring to move the rack bar 14 in a direction to increase the quantity of fuel supplied to the engine. During this time, the spring 48 and pin 49 are free to follow the action of the governor spring until the pin reaches the end of the slot 50, as is illustrated in Fig. 3. It is to be noted that in this position of "full rated load" that the stop nuts 38 are spaced from the housing 29. Upon increasing the load on the engine, the action of the governor spring causes the spring 48 to be deflected until such time as the

lock nuts 38 abut the housing thus limiting the maximum output of the engine.

The phantom lines in Fig. 3 illustrate the various elements of the governor at rated load at a lower governed speed. By rocking the lever 41 in a clockwise direction, the effective force exerted by the governor spring in opposition to the flyweights will be less due to the decreased lever ratio, thus establishing a lower governed speed of the engine. At this lower governed speed setting, the governor will function in the same manner as previously described. However, due to the decreased lever ratio, a lesser deflection of the spring 48 will be required to permit the rack bar 14 to be moved from its position at rated load, such as illustrated, to its maximum open position.

The improved engine operation resulting from the use of this governor is best illustrated by reference to Fig. 7 in which the solid lines illustrate the engine torque versus speed performance of an engine provided with thus improved governor at various governed speeds. The dotted lines illustrate the performance of the same engine provided with a conventional governor in which the force of the governor spring opposing the flyweights is varied by changing the load and deflection of the spring. It is to be noted that the solid lines from no load to full engine torque are essentially parallel, however, in the case of the engine employing a conventional governor represented by the dotted lines, the slope of the curve from no load to full engine torque becomes less as the governed speed of the engine is decreased. This characteristic is the result of decreasing the load and deflection of the governor spring to achieve a lower governed speed. By decreasing the load on the governor spring, at a certain point there will be insufficient deflection applied to the spring to move the fuel control member to its fully opened position within the operating range of the engine. Such a condition is illustrated by the 800 and 600 R. P. M. curves of the conventional governor.

Figs. 4, 5 and 6 illustrate a modified form of the governor just described in which the basic principle of operation is essentially the same. In Fig. 4, the governor is illustrated as comprising a pair of flyweights 55 pivotally supported on pins 56, each of which extends across a slot 57 provided in a collar 58. The collar 58 is carried for rotation on a shaft 59 extending from and supported by a wall of a housing 61 enclosing the mechanism. The collar 58 is provided with an integral gear portion 62 which meshes with and is rotated by a gear 63 carried on the end of an engine camshaft or the like illustrated at 64.

The flyweights are provided with inwardly extending fingers 65 adapted to engage the flanged end of a sleeve 66 carried for rotation, as well as sliding movement on the extending end of the shaft 59. At its opposite end, the sleeve 66 carries a bearing 67, the outer race of which carries a thrust disc 68. The disc 68 is adapted to abut a pair of spaced thrust blocks 69, pivotally supported on a pin 71 extending from and rigidly secured to a lever 72. The lever 72 is pivotally supported from the housing 61 by means of a pin 73 and at its uppermost end is pivotally connected to a link 74. The link 74 extends through a suitable aperture provided in the housing 61 and is pivotally connected as by a pin 75 to the rack bar 14, illustrated in Fig. 1 as controlling the quantity of fuel supplied to

the engine. During engine operation, the flyweights swing outwardly urging the lever 72 to rotate in a counter-clockwise direction as viewed in Fig. 4, thus moving the link 74 and rack bar 14 in a direction to decrease the amount of fuel metered to the engine.

The force exerted by the flyweights on the lever 72 is opposed by a governor spring 76, one end of which is pivotally connected to an ear 77 extending from the housing 61 and its opposite end to a lever 78. The lever 78 is provided with a cam like surface 79 adapted to engage a roller 81 carried for rotation on the pin 71 extending from the lever 72. The roller is interposed between the thrust blocks 69 and separated therefrom by a pair of washers 82. The opposite end of the lever 78 is pivotally supported on a shaft 83 carried in a pair of spaced arms 84 and 85, non-rotatably carried on a shaft 86, extending through and supported for rotation in the housing 61. At its outer end, the shaft 86 carries a lever 87 clamped thereto by means of a cap screw 88 and its opposite end is pivotally connected to a link 89 which may extend to any suitable manual control mechanism (not shown).

The governor spring 76 is preloaded at assembly by an amount determined by the maximum governed speed of the engine. The force exerted by it urges the levers 78 and 72 to rotate in a clockwise direction, as viewed in Fig. 4, moving the rack bar 14 in a direction to increase the amount of fuel supplied to the engine. Selection of the governed speed of the engine is accomplished by rocking the shaft 86 in the housing 61 causing the arms 84 and 85 to swing through an arc moving the lever 78 relative to the roller 81. This results in a change in the lever ratio of the spring force acting on the lever 78 to the force exerted by the flyweights acting on the lever 78 at an intermediate point through the roller 81. Rotation of the shaft 86 in a clockwise direction increases the lever ratio resulting in an increase in the governed speed of the engine while rotation in a counter-clockwise direction results in a decreased governed speed of the engine.

The shape of the cam surface 79 is such that during movement of the lever 78 relative to the roller 81, the end of the lever connected to the governor spring will move through an arc maintaining a constant spring length. As a result, the force exerted by the spring on the lever is substantially constant throughout the "no load" speed range of the engine. However, the particular shape of the cam surface may be varied to give any desired governor characteristics.

Rotation of the shaft 86 in a direction to increase the governed speed of the engine is limited by engagement of the arm 85 with a cap screw 91 having a threaded engagement with pin 92 extending from the housing 61. The cap screw 91 is adjustable to establish the maximum "no load" governed speed of the engine and is retained in its adjusted position by means of a lock nut 93. Rotation of the shaft 86 in a direction to decrease the governed speed of the engine is limited by engagement of the arm 84 with a spring loaded plunger 94 disposed within a suitable socket 95 threaded into the housing 61. Engagement of arm 84 with plunger 94 establishes the lowest idling speed of the engine and prevents the operator from inadvertently stalling it. When it is desired to completely shut off the supply of fuel to the engine, the plunger may be depressed permitting the arm 84 to engage a pin 96 carried by the 78 end of the lever 72. Engagement of the arm 84

with pin 96 establishes a positive mechanical connection with the rack bar 14 moving it to the fuel shut off position.

Fig. 4 illustrates the various elements of the governor in the position they would assume at maximum governed speed with no load on the engine. As the engine is loaded, decreasing its speed, the force exerted by the flyweights will become less permitting the governor spring to move the fuel pump control member toward the increased fuel position. Movement of the fuel pump control member toward the increased fuel position is limited by a pair of nuts 97 carried on the link 74 and adapted to engage a leaf spring 98 rigidly secured to the housing 61 by means of cap screws 99. The spring is spaced from the housing by means of a spacer 100 and serves as a resilient stop to establish a "rated load" position of the rack bar 14 below its maximum open position. When the engine is loaded in excess of its rated load, the spring 98 is deflected permitting further movement of the rack bar to increase the fuel supplied to the engine until the spring abuts the housing 61. The position the various elements assume at maximum governed speed and rated engine load is illustrated in full lines in Fig. 5. The phantom lines illustrate the position of the elements at rated load at a lower governed speed setting.

We claim:

1. In an engine governor, a fuel control member, engine actuated centrifugal flyweights acting on said member to move it toward low fuel position, a governor spring opposing the action of the flyweights and connected with said member to urge it toward full fuel position, a lever included

30

5

in the connection between the spring and said member, an adjustable spring anchor on said lever to vary the effective force of the spring, a second spring connected to the adjustable anchor at one end to oppose the action of the governor spring, and a sliding anchor for the other end of the second spring with stop means to render the spring effective only when said member approaches full fuel position.

2. In an engine governor, a fuel control member, engine actuated centrifugal flyweights acting on said member to move it toward low fuel position, a governor spring opposing the action of the flyweights and connected with said member to urge it toward full fuel position, a lever included in the connection between the spring and said member, an adjustable spring anchor on said lever to vary the effective force of the spring, a second spring connected to the adjustable anchor at one end to oppose the action of the governor spring, and a sliding anchor for the other end of the second spring with stop means to render the spring effective only when said member approaches full fuel position and a manually actuated control for varying the position of said adjustable spring anchor.
